UNITED STATES PATENT OFFICE

WALTER C. MARSHALL, OF MILWAUKEE, WISCONSIN

REFRIGERATOR

Application filed September 10, 1930. Serial No. 480,979.

My invention relates more especially to mechanical refrigerators and particularly to refrigerators wherein air circulation practically about all sides of the respective food holding compartments is effected as for example disclosed in United States Letters Patent No. 1,727,713.

The object of my invention is to provide a refrigerator having a food holding compartment or compartments about which the cold air will pass or circulate on all four sides without permitting the cold air to pass across or in actual contact with the food, with the result that the food will hold or retain its original moisture, while at the same time maintaining the food at a proper temperature.

The objects and advantages of my invention will be readily comprehended from the detailed description of the accompanying drawing, wherein:

The figure is a vertical sectional view of a refrigerator provided with my invention.

In the particular exemplification, my invention is shown applied to what may be termed a single type of mechanical refrigerator, namely a refrigerator provided with a single tier of food holding compartments 5, which may be of any convenient size and of different sizes if desired.

The invention, for purposes of illustration, has been shown applied to the type of refrigerator disclosed in Figure 6 of United States Letters Patent No. 1,727,713, consisting of the double or suitably insulated main walls 10 and the upper part of the refrigerator provided with a well known type of mechanical refrigerating unit at 11 involving fin coils 12. The unit 11 is arranged in a compartment formed by the heavy insulated walls 13 forming side and bottom walls; the side wall being arranged in spaced relation with the main wall of the refrigerator and terminating a distance removed from the top; while the bottom wall is shown sloping downwardly toward one side of the refrigerator and terminates a distance removed from the adjacent side wall of the refrigerator.

Terminating the inner side wall 13 from the top of the refrigerator as shown provides a passage 14 which establishes communica-

tion with the warm air passage or duct 15 which extends from the bottom of the refrigerator to the top of the refrigerant holding compartment and allows the tempered or warm air to rise from the food holding portion of the refrigerator and to contact with the refrigerating unit. The chilled or cold air in the refrigerant compartment passes down into the cold air duct 16 which leads to the bottom of the refrigerator.

A baffle plate 17 is preferably arranged above the opening between the downwardly sloping bottom of inner wall 13 and the main wall of the refrigerator; while said bottom of the inner wall 13 is shown preferably provided with a lip 18 for the purpose of preventing dripping of any condensate into the cold air duct 16.

With mechanical refrigerating units the copper tubes shown at 19 are usually extended downwardly toward the bottom of the refrigerator. As the refrigerating unit forms no part of my invention a more detailed showing and description of its construction need not be entered into, as any suitable type of unit may be employed.

The refrigerator, beneath the refrigerant unit holding compartment, is provided with a series of independent food holding compartments 5, preferably extending from front to rear and formed by the walls 20 and 21 of sheet metal or other suitable temperature conducting material and arranged in spaced relation with the main side walls 10 of the refrigerator so as to provide the cold air duct 16 and on the opposite side the warm air duct 15.

The inner side walls 20 and 21 are formed to support imperforate or solid plate shelves or trays 22, which may be permanently or removably secured in place and arranged in vertical distances apart to provide any desired size of food holding compartment 5.

The inner side walls 20 and 21 preferably terminate above the main bottom of the refrigerator so as to leave the passage 23 for circulation of cold air beneath the lowermost food holding compartment 5 and to establish communication between the cold air duct 16 and the warm air duct 15.

With the shelves 22 extending from front to rear of the refrigerator, a plurality of separate and non-communicating food holding compartments are provided; that is to say, separate chilling chambers for the different food articles are provided.

The side walls 20 and 21 at points immediately beneath the bottom inner wall 13 and the respective bottoms 22 of the food compartments 5, in the particular exemplification in the drawing are formed with the upwardly and outwardly bent portions 24, which may be adjustably or permanently held in place by set-screws as at 25. These portions or lips 24 may either be integral parts of the walls 20 and 21 or may be hingedly connected thereto.

With the solid side walls 20 and 21 and the solid compartment bottoms 22 it is apparent that transverse flow of the cold air is induced by the cold air from duct 16 entering the openings formed by the lips 24 in wall 20, while the tempered or warm air passes out through the opening formed by the lips 24 in the side wall 21.

It then passes into warm air duct 15 from whence it rises toward the top of the refrigerator, passing through passage 14 into the refrigerating unit compartment where it is chilled and flows down into cold air duct 16.

One of the difficulties encountered with mechanical refrigerators as at present employed is the fact that the food articles placed therein lose their original moisture and to a certain degree the natural flavor. That is to say, the food becomes dehydrated and the moisture taken from the food accumulates as frost on the cooling coils, necessitating frequent defrosting of the refrigerating unit.

In order to overcome this serious objection, I provide a cover member 26 for each food holding compartment 5.

The cover members 26 each consists of a solid or imperforate metal sheet, or other suitable temperature conducting material. These cover sheets 26 extend from front to rear of the refrigerator and inner side wall 20 to inner side wall 21 to which they may be either permanently or slidably secured.

In the particular exemplification, the cover members 26 are shown slidably held in place by opposing and spaced apart angle members 27, thus permitting the cover members to be slid forwardly through the door of the refrigerator when occasion may require.

The supporting members 27 are arranged on the inner side walls 20 and 21 adjacent to the bottoms of the outwardly flared lips 24, so that when the cover members 26 are in place air passages 28 across the top of each food holding compartment is provided, through which the cold air will pass from the cold air duct 16 to the warm air duct 15. That is to say, with my invention the cold air is made to pass along the four sides of each

food holding compartment without direct contact with the food articles.

With my improvement, separate closed food holding compartments are provided and the food in one compartment will not contaminate the food in the other compartments because escape of moisture is prevented by the substantially air-tight arrangement and the circulating air in the refrigerator is not permitted to come into contact with the food. As a result, the moisture will not be taken from the food articles and placed as a frost on the cooling coils. The defrosting operations at present required with mechanical refrigerators are not only practically eliminated or greatly reduced, but the desideratum of leaving the moisture in each compartment so that the food will retain the original moisture and flavor, while at the same time keeping the food cool or at proper temperature, is obtained.

While I have shown my invention applied to a refrigerator having a single tier of food holding compartments, it is apparent that the invention is equally adaptable to refrigerators provided with a number of tiers of compartments and that certain modifications may be made without, however, departing from the spirit of my invention.

What I claim is:

In a refrigerator of the character described, the combination of a refrigerating unit holding compartment in the top, inner vertical walls of temperature conducting material beneath said compartment arranged in spaced relation with the main side walls of the refrigerator and extending from front to rear of the refrigerator to provide a cold air duct and a warm air duct at opposite sides of the refrigerator, food holding compartments having imperforate bottoms disposed between said vertical walls, and regulable openings in the vertical walls communicating with the upper ends of the food holding compartments, with imperforate cover sheets for each food holding compartment secured to said vertical walls beneath the regulable openings and extending throughout the width and depth of the food holding compartments.
